(57) **CLAIM**

The ornamental design for air conditioning equipment, as shown and described.

DESCRIPTION

FIG. 1 is a front view of air conditioning equipment showing our new design;

FIG. 2 is a rear view thereof;

FIG. 3 is a left side view thereof;

FIG. 4 is a right side view thereof;

FIG. 5 is a top plan view thereof; and,

FIG. 6 is a bottom plan side view thereof.

The broken lines illustrate structure or features which form no part of the claimed design.
